(57) **CLAIM**

The ornamental design for an electric kettle, as shown and described.

DESCRIPTION

FIG. 1 is a front view of a first embodiment of an electric kettle, showing our new design;

FIG. 2 is rear view of the electric kettle of FIG. 1;

FIG. 3 is first side view of the electric kettle of FIG. 1;

FIG. 4 is second side view of the electric kettle of FIG. 1;

FIG. 5 is a top view of the electric kettle of FIG. 1;

FIG. 6 is bottom view of the electric kettle of FIG. 1; and

FIG. 7 is a perspective view of the electric kettle of FIG. 1.

FIG. 8 is a front view of a second embodiment of an electric kettle, showing our new design;

FIG. 9 is rear view of the electric kettle of FIG. 8;

FIG. 10 is first side view of the electric kettle of FIG. 8;

FIG. 11 is second side view of the electric kettle of FIG. 8;

FIG. 12 is a top view of the electric kettle of FIG. 8;

FIG. 13 is bottom view of the electric kettle of FIG. 8; and,

FIG. 14 is a perspective view of the electric kettle of FIG. 8.
